UNITED STATES PATENT OFFICE.

LIONEL M. WOOLSON, OF DETROIT, MICHIGAN, ASSIGNEE TO PACKARD MOTOR CAR COMPANY, OF DETROIT, MICHIGAN, A CORPORATION OF MICHIGAN.

HYDROCARBON MOTOR.

Application filed November 24, 1919. Serial No. 340,277.

This invention relates to hydrocarbon motors and particularly to carbureting and mixture heating devices therefor.

One of the objects of the present invention is to provide means for supplying a combustion heater with some of the mixture from the idling device of the motor carburetor.

Another object of the invention is to provide a carburetor having special idling means, with means for withdrawing some of the mixture from said idling means for use in a combustion heater or similar device.

Another object of the invention is to provide a slow acting vibrator for the igniter of a combustion heater.

Other objects of the invention will appear from the following description taken in connection with the drawings which form a part of this specification, and in which—

Figure 1 is a vertical section through a carburetor and heater device embodying my invention, the igniter means being shown largely in diagram; and

Figure 2 is a similar section showing another form of my invention.

Referring to Figure 1 of the drawings, 10 is a cylinder block of a hydrocarbon motor, four or six cylinders usually being cast in a single block, and 11 is the horizontal inlet conduit for the combustible mixture which passes to the motor cylinders.

Detachably secured to the cylinder block, as by bolts 12, is a horizontal pipe section 13 which comprises also a heater device in the form of a combustion chamber 14, the combustion chamber completely surrounding or jacketing a part of the pipe section 13. The interior passage 15 in the pipe section forms a continuation of the intake conduit 11 of the motor and the mixture from the carburetor of course passes through this conduit 15.

The combustion heater 14 is supplied with a suitable mixture through a small inlet port 16 and a screen 17 and the mixture is ignited by a suitable igniter 18 which is somewhat like the usual spark plug of the motor. The burnt gases pass from the combustion chamber 14 through a pipe 19 into the intake conduit 15 at 20. Thus heat is transferred through the wall of the pipe section 13 and the hot burnt gases passing from the combustion chamber into the intake conduit come in direct contact with the

mixture passing from the carburetor to the motor and thereby further heat the mixture.

The spark plug or igniter 18 has one of its terminals 21 grounded on the engine in the usual way, and its other terminal 22 is connected through a porcelain 23 to a conductor 24 which receives high tension current from a transformer coil 25. The transformer coil is connected through a vibrator device, indicated generally at 26, to a generator or high frequency magneto 27 which is somewhat diagrammatically illustrated. It will be understood, however, that the particular form of generator shown is of the well known "Ford" type. Conductors 28 and 29 connect the generator 27 to the vibrator 26 and the vibrator to the transformer coil 25.

Since the combustion chamber 14 is continuously supplied with mixture while the motor is running, it is usually only necessary to start the mixture burning when it will thereafter be self-sustaining. It is advisable, however, to continue the spark in the chamber at intervals in order to reignite the mixture should the flame be extinguished for any reason, but obviously it is not necessary to have the rapid shower of sparks that would be produced by the ordinary vibrator. The present invention, therefore, provides a slow moving vibrator and two means of slowing down the vibrator are illustrated, either or both of which may be used as desired.

One means of slowing down the vibrator comprises a copper tube 30 which surrounds the core 31 which is usually of Swedish iron and is arranged between said core 31 and the winding 32 of the coil of the vibrator. This causes a lag in the operation of the vibrator and hence slows it down in the desired way.

The second means for slowing down the vibrator comprises a dash-pot 33 which is directly connected to the vibrator arm 34 to thereby act directly upon the vibrator to slow down its action.

Directly connected to the horizontal pipe section 13 is a carburetor 40, the main parts of which are similar to those of the well known "Ford" carburetor. Thus the carburetor comprises a float chamber 41 to which the liquid fuel or gasoline is fed in the well known manner and maintained at a given level by a suitable float 42. The mix-

ing conduit or chamber 43 dips down into the float chamber and has an air inlet 44 which is controlled for choking by a hand operated butterfly valve 45. The mixing conduit 43 is supplied with gasoline from the float chamber 41 through a port 46 and a passage 47 which passage is controlled by a needle valve 48. An overflow passage 49 extends diagonally, as shown, and prevents the fuel from rising too high in the mixing chamber.

The carburetor outlet conduit or chamber 50 is arranged just above the mixing chamber 43 and is connected with it by a passage 51 which is controlled by a weighted valve 52 pivoted at 53. A bumper or weight 54 is mounted in a sleeve 55 just above the valve 52, and the bumper and sleeve are retained by a cap 56. The bumper quiets the action of the valve 52 and prevents it from opening too wide.

A throttle valve 57, of the butterfly type, is shown in the outlet conduit 50, the mixture from the carburetor thus being controlled by the operator.

From the above it will be seen that in the normal operation of the carburetor, with the throttle valve 57 partly opened and the motor working above its idling speed, the suction will somewhat lift the valve 52 and air will be drawn into the mixing chamber 43 through the air intake 44. This air will pick up some of the gasoline in the bottom of the mixing chamber and thereby form a suitable combustible mixture which is carried through the outlet conduit 50, past the throttle 57 and into the conduit 15, from which conduit it is delivered to the motor. As the suction increases the valve 52 is opened wider and a greater amount of mixture is drawn through the carburetor.

For idling the motor it is intended that the valve 52 shall remain closed and a small amount of mixture shall be drawn through a tube 58 which is arranged in the wall between the mixing chamber 43 and the outlet chamber 50. This tube extends substantially vertically and its lower open end 59 is just above the upper end of the passage 47 and dips into the puddle of gasoline formed in the lower part of the mixing chamber 43 when the motor is not running. Near the lower end of the tube 58 and about at the level of the upper end of the overflow passage 49 are one or more lateral openings 60.

Formed as an integral part of or separate from the tube 58 is a second tube 61, above and in line with the tube 58. The ends of these tubes abut if they are made separately and one or the other of them is provided with lateral openings 62 into the outlet chamber 50 of the carburetor. Thus the suction of the carburetor, when the motor is running slowly and the throttle valve

nearly closed, is sufficient to draw a small amount of mixture through the tubes 58 and 61 into the outlet passage 50 to thereby keep the motor running slowly, air being supplied to the tube 58 through the openings 60 and gasoline coming into the tube through its lower end.

For the purpose of withdrawing some of the idling mixture to supply the combustion heater 14, the tube 61 is extended upwardly in the form of an elbow 63 and the outlet 64 of this elbow is connected by a pipe 65 with the port 16 hereinabove described. Thus the suction of the motor draws some of the mixture directly into the outlet passage 50 through the port 62, and this same suction draws some of the mixture into the combustion chamber 14 through the tube 61 and pipe 65. The size of the openings 60 and 62, as well as the opening in the lower end of the pipe 58, are suitably proportioned to supply sufficient mixture for both the motor and the combustion chamber.

In the form shown herein, the needle valve 48 is extended upwardly through both the tube 58 and tube 61 and is threaded into the elbow 63 as at 66. Its upwardly projecting end has a knurled flange 67 so that the needle valve may be readily turned to adjust the size of the passage 47, thus regulating the quantity of gasoline that may be supplied to the mixing chamber 43.

Referring to Figure 2 of the drawings, the invention is shown as applied to a carburetor having a movable idling tube. The main parts of the carburetor are similar to those of the well known Dodge carburetor and comprise in general an air chamber 70 having a vertical hollow guiding tube 71 therein extending upwardly into a passage 72 which leads to a mixing chamber 73. The passage 72 is controlled by an automatic or compensating valve 74 which slides vertically relative to the tube 71. This valve 74 also controls the amount of liquid fuel entering the carburetor and for this purpose it has a stem 75 which extends through the tube 71 and terminates in a piston 76 having one or more valves 77 therein, the piston 76 operating in a cylindrical well 78 arranged below the air chamber 70. The well 78 is supplied with gasoline through a passage 79 from a float chamber 80, which chamber, by means of the usual float 81, maintains the gasoline at a given level. The stem 75 above referred to has a passage 82 therethrough and a tapered metering pin 83 extends upwardly from the bottom of the well 78 into the passage 82, as shown. Ports 84 connect the well 78 with the passage 82 and it will be seen that if the stem 75 is moved upwardly the passage 82 which surrounds the metering pin 83 is enlarged to permit the passage of more fuel, and as the stem 75 is moved downwardly the pas-

sage is decreased in size. This up and down movement of the stem 75 is controlled by the piston 76 which acts as a dash-pot for the upward movement of the stem, the valve 77, however, opening to permit the stem to pass downward freely.

Since the stem 75 and the valve 74 are rigidly connected they, of course, move together and the valve and stem are caused to move by the suction of the motor. When the valve is in its lowest position, as shown in the drawing, no air can pass around its circumference, but as soon as the motor creates suction in the chamber 73 the valve 75 is raised and the farther it is raised the greater the air opening and the greater the fuel opening in the passage 82.

In the drawing the metering pin 83 is shown as manually adjustable, as by an arm 85 connected to a pinion 86 which meshes with a rack 87 on the lower end of the pin 83. A spring 88 yieldingly retains the pin in its uppermost position.

The valve 74 above referred to has the gasoline nozzle 89 formed in it and the upper flared end of the nozzle 89 is surrounded by an air passage 90 which is fed by a series of air passages 91 and 92 which extend through the valve 74 and communicate with the air chamber 70. Thus when the valve 74 is in its seated position, as shown in the drawing, there is a free air passage through the passages 92, 91 and 90 so that when there is not enough suction from the motor to raise the valve 74 there will be a relatively high degree of suction through the passage 90 past the edge of the nozzle 89 and there will, of course, also be suction in the nozzle 89 so that air and gasoline will be drawn into the mixing chamber 73.

In the form of the invention shown, the upper part of the valve 74 is formed with a tubular extension 93 having lateral ports 94 communicating with the mixing chamber 73. Extending downwardly into the tube 93 is a second tube 95 and the tube 93 slides on the tube 95 or relatively to it as the valve 74 rises and falls with the varying suction of the motor. This telescoping of the tubes 93 and 95 provides communication between the interiors of those tubes and the tube 95 thus draws off some of the mixture from the tube 93 and carries it to a combustion chamber 14' which surrounds the intake conduit 15' leading from the upper end of the mixing chamber 73.

As this form of the invention is illustrated, the chamber 73 and the conduit 15' are formed in a single casting which is an elbow in which the conduit 15' is the horizontal part and the chamber 73 the vertical part. The pipe 15 is formed as an integral part of the casting and is in the bent part of the elbow. Its communication with the heater 14' is through a restricted port 16'

and a screen 17'. A spark plug 18' ignites the mixture in the chamber 14'.

The usual throttle valve 57' is provided and the casting is connected to the motor 10 by suitable bolts 12, the intake conduit 15' 70 communicating with the passage 11 as in the form shown in Figure 1.

The outlet from the combustion chamber 14' is through a passage 19' in a plug fitted in the wall of the casting. 75

It will be seen that the normal operation of the carburetor in supplying the motor with a suitable mixture is not in any way interfered with by the tube 93, except that the air and gasoline openings are so adjusted 80 that the idling passages will supply sufficient mixture to the tube 93 to feed both the motor and the combustion heater.

Other forms than those shown above may be devised without departing from the spirit 85 or scope of this invention.

Having thus described my invention, what I claim and desire to secure by Letters Patent is:

1. In a hydrocarbon motor, the combination with a carburetor having an idling conduit, of a combustion heater, and means connecting said idling conduit to supply mixture to said combustion heater. 90

2. In a hydrocarbon motor, the combination with a carburetor having a mixing tube for operation principally in idling the motor, of a combustion heater, and means connecting said tube to supply mixture to said heater. 95

3. In a hydrocarbon motor, the combination with a carburetor having a mixing tube for operation principally in idling the motor, of a combustion heater, and means for drawing mixture from said mixing tube and 105 supplying it to said heater.

4. A carburetor comprising a main mixing device and an auxiliary mixing device, both of said devices being adapted to deliver mixture to a single outlet of the carburetor, and a connection for withdrawing part of 110 said mixture from said auxiliary device.

5. In a hydrocarbon motor, the combination with a carburetor having a main mixing chamber, and an idling tube, of a combustion heater connected to receive mixture from said idling tube. 115

6. In a hydrocarbon motor, the combination with a carburetor having a main mixing chamber, and an idling tube, of a combustion heater having an outlet pipe connection to the motor intake pipe, and a suction pipe from said heater to said idling tube. 120

7. A carburetor comprising a mixing chamber having an outlet conduit, means for supplying liquid fuel to said chamber, an idling tube extending into said mixing chamber, and two separate outlet means 125 from said idling tube. 130

8. A carburetor comprising a mixing chamber having an outlet conduit, means for supplying liquid fuel to said chamber, an idling tube extending into said mixing chamber, outlet means from said idling tube to the carburetor outlet, and another outlet means from said idling tube.
9. A carburetor comprising a mixing chamber, means for supplying liquid fuel thereto, an idling tube extending into said mixing chamber, a tube forming a continuation of the idling tube and connected thereto, said continuation tube having lateral openings permitting some of the mixture from the idling tube to pass to the carburetor outlet, and another outlet means from said continuation tube.
10. A carburetor comprising a mixing chamber having an air inlet and a valve controlled outlet, a mixture outlet passage from said carburetor communicating with the outlet from said mixing chamber, means for feeding fuel to said mixing chamber, an idling conduit passing around the valved outlet of the mixing chamber, and means for withdrawing part of the mixture from said idling conduit.
11. A carburetor comprising a mixing chamber, an outlet chamber above the mixing chamber, there being a passage between said chambers, a valve controlling said passage, a tube at one side of said valve and extending through the wall between said chambers to thereby form a bypass from the mixing chamber to the outlet chamber around said valve, and a second tube connected to the outlet of said first tube and adapted to draw part of the mixture therefrom.
12. A carburetor comprising a mixing chamber, an outlet chamber above the mixing chamber, there being a passage between said chambers, a valve controlling said passage, a tube at one side of said valve and extending through the wall between said chambers to thereby form a bypass from the mixing chamber to the outlet chamber around said valve, and a second tube connected to the outlet of said bypass tube and having lateral openings to permit part of the mixture from said bypass tube to pass to the outlet chamber.
13. A carburetor comprising a mixing chamber, an outlet chamber above the mixing chamber, there being a passage between said chambers, a valve controlling said passage, a tube at one side of said valve and extending through the wall between said chambers to thereby form a bypass from the mixing chamber to the outlet chamber around said valve, and a second tube connected to the outlet of said bypass tube and having lateral openings to permit part of the mixture from said bypass tube to pass to the outlet chamber.
- bers to thereby form a bypass from the mixing chamber to the outlet chamber around said valve, and a second tube passing through the upper wall of the outlet chamber and into communication with the outlet end of said bypass tube to thereby withdraw mixture from said bypass tube and lead part of it out of the carburetor independently of said outlet chamber.
14. In a hydrocarbon motor, the combination with a motor cylinder block having a horizontal inlet passage, of a horizontal pipe section secured to said block at said passage and having a combustion heater connected thereto, a carburetor connected to the inlet end of said pipe section, said carburetor having an idling tube, and a pipe connection from said idling tube to said combustion heater.
15. In a hydrocarbon motor, the combination with the motor intake conduit, of carbureting means connected to said conduit and comprising a float chamber, a main mixing device and an auxiliary mixing device, both of said devices being adapted to draw liquid fuel from said float chamber and deliver a mixture to said intake conduit, a combustion heater having an outlet to said intake conduit, a suction pipe connection from said heater to the mixture of said auxiliary mixing device.
16. In a hydrocarbon motor, the combination with the motor intake conduit, of carbureting means connected to said conduit and comprising a main mixing device and an auxiliary mixing device, both of said devices being adapted to deliver mixture to said intake conduit, a combustion heater having an outlet to said intake conduit, and a suction pipe connection from the mixture of said auxiliary device to the intake side of said heater.
17. In a hydrocarbon motor, the combination with the motor intake conduit, of carbureting means connected to said conduit and comprising a float chamber, a main mixing device and an auxiliary mixing device including an idling tube, both of said devices being adapted to draw liquid fuel from said float chamber and deliver mixture to said intake conduit, a combustion heater having an outlet to said intake conduit and subject to the suction therein, and a suction pipe connection from said idling tube to said combustion heater.

In testimony whereof I affix my signature.
LIONEL M. WOOLSON.
